UNITED STATES PATENT OFFICE.

SAMUEL HOUSTON JACOBSON, OF NEW YORK, N. Y., ASSIGNOR TO NATIONAL VENTILATING COMPANY, OF NEWARK, NEW JERSEY, A CORPORATION OF NEW JERSEY.

VENTILATOR.

SPECIFICATION forming part of Letters Patent No. 779,653, dated January 10, 1905.

Application filed April 2, 1903. Serial No. 150,716.

To all whom it may concern:

Be it known that I, SAMUEL HOUSTON JACOBSON, a citizen of the United States, residing at New York city, New York, have invented certain new and useful Improvements in Ventilators, of which the following is a specification.

My invention is designed for the production of an improved ventilator especially intended for use upon cars and the like and upon stationary building structures where the opening leading to the space to be ventilated is of comparatively large area.

The invention relates particularly to that class of ventilators in which a casing provided with open ends is employed which covers the opening communicating with the space to be ventilated and has mounted therein a series or group of pivotally-mounted deflecting blades or wings connected together at their free ends, so that they may all be moved in unison and be constantly maintained parallel to each other.

The object of the invention is to provide means whereby the series or group of deflecting blades or wings may be automatically moved from one of its positions to the other by the smallest possible air-pressure due to a change in the direction of movement of the car or other vehicle to which the device is applied or to a change in the direction of movement of the wind.

Other objects of the invention will herein-after appear, and that which I regard as new will be set forth in the claims.

In the drawings forming part of this specification, Figure 1 is a cross-section of the upper part of a car with my improved ventilator applied thereto. Fig. 2 is a horizontal longitudinal section of the ventilator, and Fig. 3 is a detail view of one of the deflecting blades or wings.

Like reference-numerals indicate like parts in the different views.

My improved ventilator has been shown as applied to a car, although, as stated, it is capable of and intended for use upon a stationary building structure.

The upright wall 1 of the car between the

decks is provided with an elongated opening 50 communicating with the space to be ventilated, and the casing 3 of the ventilator is secured thereto. The said casing covers the opening 2 and is closed on its three outer sides. The opposite ends of said casing are open, 55 however, and have been shown as provided with funnels or expanded portions 4 and 5. Within the casing 3 is a series or group of deflecting blades or wings 6 7 8, the same being shown as pivotally mounted at their inner ends adjacent to the outer surface of the wall or partition 1 of the car substantially in line with the outer or free edge of the opening 2. The outer ends of said deflecting-blades are connected together, so as to be constantly 65 maintained parallel to each other and so as to be moved in unison by a rod or wire 9. The particular shape of this rod and the means of connecting it to the deflecting-blades are immaterial. It has been shown, however, as 70 provided at intervals with eyes 10, which fit within loops 11, projecting from the side edges of said blades. The pivots 12, on which the intermediate blades or wings 7 are mounted, all lie opposite the opening 2 in the wall 1 of 75 the car. The pivots 13 and 14, however, on which the outer blades 6 and 8 are respectively mounted, are located beyond the ends of the opening 2 or opposite the imperforate portions of the wall 1. Stops 15 and 16 are 80 provided for limiting the pivotal movements of the deflecting blades or wings in opposite directions, the said stops being shown in the form of connecting or tie rods between the upper and lower walls of the casing 3. The 85 stop 15 is adapted to be engaged by the inner surface of the deflecting blade or wing 6, and the stop 16 is adapted to be engaged by the inner surface of the deflecting blade or wing 8. The said stops may be otherwise disposed, 90 or additional ones may be provided, if desired. The blade 6 is provided with a finger or projection 17, extending from the side edge thereof, and the blade 8 is provided with a similar finger or projection 18. These fingers or projections have been shown in the form of loops of wire secured to the blades to which they are connected and extend to such a distance

that during the movements of said blades from one position to another they will just escape the inner surface of the side wall of the casing 3. Coöperating with these parts are the valves 5 19 and 20, shown in the form of pivoted flaps. The valve 19 is preferably pivoted adjacent to the point of intersection of the funnel or expanded portion 4 with the body of the casing 3 and the valve 20 adjacent to the point of intersection 10 of the funnel or expanded portion 5 with the body of said casing. Each of said valves is of such length that when the series or group of deflecting-blades is inclined toward it it will reach from its pivot to the adjacent end blade or wing of the series to co-operate with said end blade and cut off the passage of air through the casing 3, at the inlet end thereof. Both of said valves are capable of being moved to positions within the 15 casing 3 against or in comparatively close relation to the inner surface of the side wall thereof, and both are capable of being moved outwardly within the adjacent expanded portions or funnels 4 and 5 substantially in line 20 with the outer wall of the casing, but separated from the inner surfaces of said funnels. The latter positions may be maintained by means of the stops or projections 21 and 22, secured, respectively, to the funnels 4 and 5. 25 30 Any other equivalent means, however, may be substituted for that shown.

If my improved device be mounted upon a car which is moving in the direction of the arrow in Fig. 2 of the drawings, the deflecting-blades 6, 7, and 8 will lie at an angle to the plane of the opening 2 in the wall 1, with the free ends thereof extending to the rear, the valve 19 will lie within the casing 3 in comparatively close relation to the inner 35 surface of the side wall thereof, and the valve 20 will lie within the funnel 5 in contact with the stop 22. A current of air will then pass through the casing of the ventilator, the same being compressed by the inlet-funnel 4 and 40 by being forced through the contracted space between the deflecting-blades and the side wall of said casing and discharged from the exit-funnel or expanded portion 5. The result will be that the foul or vitiated air within the 45 car will be withdrawn through the opening 2 and be discharged through the rear end of the casing 3. In other words, an induced current will be created outwardly through the opening 2, which will carry off the foul air and 50 gases, while at the same time the direct current of air entering at the forward end of the casing 3 will be cut off from the car. It will therefore be impossible for any smoke, dust, cinders, or other foreign matter to be admitted 55 to the car through the opening 2. If the movement of the car be reversed or if the car be at a standstill and the direction of the wind change, the air will enter the opposite end of the casing 3 through the funnel or expanded 60 portion 5. The first action of the air, how-

ever, will be to throw the valve 20 around from its position in engagement with the stop 22 to the position shown in dotted lines in Fig. 2 of the drawings—that is, to a point where the same lies in contact with the outer end of the blade or wing 8. The said valve now co-operates with the blade 8 to cut off the passage through the casing 3 at the inlet end thereof and to direct or apply the full force of the current against said blade to cause the 70 automatic shifting of the series of blades to its reverse position. This closing of the inlet end of the casing also prevents the entrance of air to the interior of the car through the opening 2 while the deflecting-blades are in 75 position to permit it. As the current of air continues or increases the whole of it is directed against the blade or wing 8 and the valve 20. The result is that both of these parts are moved together on their pivots until 80 the inner or free end of the valve 20 passes beyond the finger or projection 18 on the blade 8. When the valve 20 moves out of contact with the finger 18, the blade 8, and with it, through the connecting-rod 9, all of 85 the other deflecting-blades 6 and 7, will be moved on its pivot independently of said valve until the series of deflecting-blades lies in a position the reverse of that which it formerly occupied—that is, the free ends of said blades 90 will extend toward the expanded end 4 of the casing. This position will be determined by the engagement of the blade or wing 8 with the stop 16. The blade 6 is of course moved with the other deflecting-blades, and as it is 95 turned forwardly the finger or projection 17 thereon engages the free end of the valve 19, turning the latter from its position within the casing 3 and moving it outwardly. The 100 said valve 19 is then moved by the air-current, which may now act upon it, out to its position within the funnel 4 in engagement with the stop 21. The current of air may now pass 105 freely through the casing of the ventilator and act as before to remove by induction the 110 foul or vitiated air from the interior of the car through the opening 2.

Were it not for the provision of the valves 115 19 and 20 and the parts which co-operate therewith or an equivalent construction there would be no way by which the series or group of deflecting-blades could be automatically and with certainty moved from one of its positions to the other, for the reason that when the direction of movement of the current of 120 air or of the car or other moving body changed there would still be a passage through the casing of the ventilator. In other words, the air would not be forced to act wholly upon one or more of the deflecting-blades to reverse 125 the position of the series. The result would be that instead of withdrawing the foul or vitiated air from the interior of the car by induction a draft of air carrying with it smoke, dust, and other foreign particles would be 130

caused to enter the car through the opening 2. By my invention a reversed current of air of the smallest possible pressure will act instantly to change the positions of the deflecting-blades which go to make up the group or series. A ventilator is thus produced which is entirely automatic in its action, which is extremely sensitive, and which is thoroughly effective in withdrawing the foul air from the space to be ventilated and in preventing the introduction of smoke, cinders, dust, and the like into the said space.

Guards or deflectors 23 have been shown adjacent to the pivots 13 and 14 of the blades 6 and 8 for preventing the passage of air behind said pivots, and a door 24 has also been shown for controlling the passage through the opening 2 from the inside of the car. These parts may be of any suitable construction.

Having now described my invention, what I claim as new, and desire to secure by Letters Patent, is—

1. In a ventilator, a casing covering an opening communicating with the space to be ventilated and having its ends open, a series of pivoted deflecting-blades therein, and movable means, automatically thrown into operation when a change takes place in the point of entrance of the air-current to said casing, for directing the full force of said current against said blades, as and for the purpose set forth.

2. In a ventilator, the combination with a casing covering an opening communicating with the space to be ventilated, and a series of deflecting-blades pivoted at their inner ends in line with the outer edge of said opening, of a pair of valves or flaps pivoted within said casing adjacent to the outer ends thereof, the inner ends of said valves being adapted to engage the end blades of said series when the latter are directed toward said valves and to pass by said blades when the latter are directed away from said valves, as and for the purpose set forth.

3. In a ventilator, the combination with a casing covering an opening communicating with the space to be ventilated, and a series of deflecting-blades pivoted at their inner ends in line with the outer edge of said opening, of a pair of valves or flaps pivoted within said casing adjacent to the opposite ends thereof, the said valves being adapted to engage the end blades or wings of said series when the latter are directed toward said valves and to pass by said blades when the latter are directed away from said valves, and stops for limiting the outward movements of said valves, as and for the purpose set forth.

4. In a ventilator, the combination with a casing covering an opening communicating with the space to be ventilated, having its ends open and having funnels or expanded portions on said ends, and a series of deflecting-blades pivoted at their inner ends in line with the outer edge of said opening and connected together so as to be moved in unison, the outer blades of said series being pivoted at points beyond the opposite ends of said opening, of valves or flaps pivoted at the points of intersection of said funnels with said casing, the said valves being adapted to engage the end blades of said series when the latter are directed toward said valves, and to pass by said blades when the latter are directed away from said valves, and stops for limiting the outward movements of said valves and for holding them away from the inner surfaces of said funnels, as and for the purpose set forth.

5. In a ventilator, the combination with a casing covering an opening communicating with the space to be ventilated and having its ends open, and a series of deflecting-blades pivoted at their inner ends in line with the outer edge of said opening and connected together so as to be moved in unison, the outer blades of the series being pivoted at points beyond the opposite ends of said opening and having fingers or projections thereon, of a pair of pivoted valves or flaps mounted adjacent to the opposite ends of said casing, the said valves being adapted to engage the end blades of said series when the latter are directed toward said valves, and to pass by the said blades and lie adjacent to the inner surface of said casing when the said blades are directed away from said valves, said valves being further adapted to be engaged and moved outwardly by said fingers, when said series of blades is shifted from one of its positions to the other, as and for the purpose set forth.

6. In a ventilator, the combination with a casing covering an opening to the space to be ventilated and a reversible deflecting-blade pivoted to that side of the casing next the opening, of a supplemental blade or valve pivoted to the opposite side in position to be caught by a change in the direction of the air-current and direct the full force of said air-current against the first-named blade.

In testimony whereof I have hereunto set my hand in presence of two subscribing witnesses.

SAMUEL HOUSTON JACOBSON.
